UNITED STATES PATENT OFFICE

OTTO I. QUILLIN AND CLAUDE R. WRIGHT, OF COLORADO SPRINGS, COLORADO

ADVERTISING DEVICE

Application filed May 29, 1930. Serial No. 457,390.

This invention relates to an apparatus for displaying advertisements, and has for one of its objects to provide an apparatus of this character which shall be especially adapted for use in automobile and other camps, which shall be simple and highly efficient, and which shall be adapted to be operated cheaply and maintained in a highly efficient condition at comparatively low cost.

With the foregoing and other objects in view, the nature of which will appear as the description proceeds, the invention consists in the construction, combination and arrangement of parts hereinafter fully described and claimed, and illustrated in the accompanying drawings, wherein:

Figure 1 is a sectional view taken on a vertical plane extending longitudinally and centrally through the apparatus;

Figure 2 is a view in front elevation of the apparatus;

Figure 3 is a sectional view taken on the vertical plane indicated by the line 3--3 of Figure 1;

Figure 4 is an elevational view of a fragmentary portion of the advertising card carrying chain of the apparatus, and

Figure 5 is a diagrammatic view of the motor and lamp circuits of the apparatus.

The apparatus comprises a casing 1 which is by preference in the form of that type of cottage found in tourists and other camps. The bottom wall 2, side walls 3, front and rear walls 4 and 5, and top walls 6 of the casing 1 are made of fire-proof material and are secured together and reinforced by a metal frame 7. The front wall 4 is provided with a window 8 through which the advertisements are displayed.

A metal frame 9 is located in the casing 1, and consists of lower and upper side bars 10 and 11, respectively, lower and upper front end bars 12 and 13, respectively, and lower and upper rear end bars 14 and 15, respectively. The frame 9 also comprises cor-

ner bars 16 which extend below the lower side and end bars to provide legs 16^a by which the frame is supported in the casing 1.

Lower and upper front drums 17 and 18, respectively, and lower and upper rear drums 19 and 20, respectively, are rotatably supported within the frame 9 by shafts 21 which are journaled in bearings 22 fixed to the frame bars 10 and 11. The drums 17-20 are similar, and are fixed to the shafts 21, as at 23. Each of the drums 17-20 comprises a pair of heads 24 and cross bars 25 which are arranged between and terminally fixed to the heads. The cross bars 25 are located near the peripheries of the heads 24 and are arranged in equally spaced relation in the direction of the circumference of the drums.

The drums 17-20 support an endless chain 26 which is made up of links each of which consists of a plate 27 and side bars 28 formed integrally with the plate. The bars 28 extend longitudinally beyond the plates 27 and have their terminals pivotally connected, as at 29. The terminals of the bars 28 are provided with notches 30 for the reception of 70 the drum bars 25 to effect a driving connection between the drums 17-20 and the chain 26. The distance between the end walls of the notches 30 of each link bar 29 is slightly less than the distance between each pair of 75 the bars 25 of each drum, and the link bars engage the drum bars between the drum heads 24, so as to prevent any longitudinal or lateral movement of the chain 26 with respect to the drums 17-20. Holders 31 for cards 80 32 bearing advertising matter, are riveted to the outer sides of the chain links, as at 33. The holders 31 are provided with opposed channels 34 which extend transversely of the chain 26 and in which opposed edges of the advertising cards 32 are positioned to secure the cards to the holders.

The front drums 17 and 18 are arranged below and above the window 8 of the casing 1, and that run of the chain 26 that extends between these drums 85 90 95

occupies a vertical position so as to permit the advertising cards 32 to be presented squarely before the window.

The drums 17-20 are intermittently rotated to successively present the advertising cards 32 before the window 8, and the interval of time between each rotation of the drums is sufficiently long to permit the advertising matter on the cards to be read and studied.

10 The means for rotating the drums 17-20 comprises an electric motor 35, a disc 36 provided with a wrist pin 37, and a Geneva gear 38 adapted to be engaged by the wrist pin and adapted to engage the cross bars 25 of the 15 drum 20.

The disc 36 is driven from the motor 35 at a comparatively slow rate by a pinion 39 fixed to the armature shaft 40 of the motor and a gear wheel 41 fixed to the disc 36. The 20 diameter of the disc 36 is equal to that of the drum heads 24, and the wrist pin 37 is spaced from the center of the disc for a distance equal to the distance between the centers of the drum heads and cross bars 25, to the end that 25 the disc and drum heads may be struck up from sheet metal by the same die. The wrist pin 37 moves into and out of engagement with the Geneva gear 38 once during each rotation of the disc 36. During each actuation 30 thereof by the wrist pin 37, the Geneva gear 38 moves out of engagement with one of the cross bars 25 of the drum 20 and into engagement with the next adjacent cross bar of this drum with the result that the chain 35 26 will be intermittently moved to successively present the advertising cards 32 before the window 8, and will be held against accidental movement during its idle periods to permit the advertising card before the window to be 40 easily read and studied.

The motor 35 is mounted upon a bracket 42 fixed to the frame 9. The disc 30 and the gear wheel 41 are journaled upon a shaft 43 supported by hangers 44 fixed to the frame 45.

45 The Geneva gear 38 is journaled on a shaft 45 carried by hangers 46 fixed to the frame 9.

The advertising card 32 before the window 8 is illuminated by an electric lamp 47 arranged within the casing 1, the rays of the 50 lamp being directed onto the front side of the advertising card by a reflector 48. A source of current, which for the purpose of illustration is shown as consisting of a battery 49, is provided for the motor 35 and lamp 47. The battery 49 is connected to the brushes of the motor 35 by conductors 50 and 55 51 in the former of which is arranged a switch 52. One terminal of the lamp 47 is connected by a conductor 53 to the switch 52, and the other terminal thereof is connected by a conductor 54 to an arcuate contact 55 fixed to the frame 9, as at 55a. A brush 56 60 which cooperates with the contact 55 to close the lamp circuit, is connected by a conductor 57 to the conductor 51 and is carried by the 65

disc 36 inwardly of and diametrically aligned with the wrist pin 37. The contact 55 and brush 56 constitute an automatic switch for the lamp 47, and such switch is closed while an advertising card is stationary before the 70 window 8 and is opened while such card is being moved away from the window and another one is being moved into display position with respect to the window.

75 It should be apparent from the foregoing description, taken in connection with the accompanying drawings, that it is only necessary to close the switch 52 when it is desired to start the apparatus, and that the apparatus will continue to operate until the switch is 80 opened.

85 During the operation of the apparatus, the advertising cards will be successively moved into display position with respect to the window 8. When an advertising card reaches this position, the chain 26 will come to rest and the circuit of the lamp 47 will be closed. After an advertising card has been displayed for a predetermined period of time, the circuit of the lamp 47 will be opened and the 90 chain set in operation to effect the movement of the advertising card from the window and to present another one thereto. When another card is presented before the window, the circuit of the lamp 47 will be 95 again closed.

100 It should be also understood that the apparatus is simple, durable and highly efficient, that it may be manufactured and sold at a comparatively low cost and that it is fire-proof.

105 While we have described the principle of the invention, together with the structure which we now consider the preferred embodiment thereof, it is to be understood that the structure shown is merely illustrative and that such changes may be made, when desired, as fall within the scope of the invention as claimed.

110 We claim:—

1. An advertising device, comprising a casing having a window, a series of drums rotatably supported in the casing and each embodying a pair of heads and cross bars terminally connected to the heads, an endless chain 115 mounted upon the drums between the heads thereof and embodying links having notches for engagement with the cross bars, means for securing advertising cards to the chain, and means for intermittently operating the 120 drums to successively present the advertising cards to the window.

2. An advertising device, comprising a casing having a window, a series of drums rotatably supported in the casing and each embodying a pair of heads and cross bars connected to the heads, an endless chain mounted upon the drums between the heads and embodying links having bars provided with 125 notches for engagement with the cross bars, a 130

disc rotatably mounted in the casing and provided with a wrist pin, a Geneva gear rotatably mounted in the casing for engagement by the wrist pin and for engagement 5 with the cross bars of one of the drums, and means for rotating the disc.

In testimony whereof we hereunto affix our signatures.

OTTO I. QUILLIN.
CLAUDE R. WRIGHT.
